UNITED STATES PATENT OFFICE.

NELVIA E. RITCHIE, OF KANSAS CITY, MISSOURI.

CLOTHES-RETAINER FOR RAILWAY-CAR SLEEPING-APARTMENTS.

1,274,937.

Specification of Letters Patent.

Patented Aug. 6, 1918.

Application filed April 22, 1912. Serial No. 692,272.

To all whom it may concern:

Be it known that I, NELVIA E. RITCHIE, a citizen of the United States, residing at Kansas City, in the county of Jackson and 5 State of Missouri, have invented certain new and useful Improvements in Clothes-Retainers for Railway-Car Sleeping-Apartments, of which the following is a full, clear, and exact description, such as will enable others 10 skilled in the art to which it appertains to make and use the same.

The invention relates to clothes retainers for sleeping apartments for railway cars and seeks to provide a simple and efficient form 15 of retainer with ample provisions for retaining the clothes of the occupants in suitable condition when removed on retiring.

Railway sleeping apartments are usually provided with walls at either end, curtains 20 hung from a pole at the entrance side of lower and upper berths, the lower side of each berth comprising a bed. It is essential that sleeping apartments be supplied with retainers to retain the clothing of the occupants 25 when removed on retiring, so that on arising the clothes will be in presentable condition. For this reason sleeping apartments must be supplied with clothes retainers constructed to retain clothing in a neat 30 and uncrumpled condition, and located easily accessible from the bed, which is located within the apartment or berth.

The present invention seeks to provide an improved clothes retainer for sleeping 35 apartments to receive the occupant's clothes when removed on retiring so that the clothes will be retained in a presentable condition. It is customary to provide a box, or trough, at either end of the berth for clothing and 40 a swinging hammock hanging within the berth, but by providing retainers that will retain the clothing in a smooth, presentable, uncrumpled condition, much annoyance and inconvenience will be removed from the traveling public, as all travelers know that their 45 clothes are usually ruined by a trip in the usual form of sleeping car.

Another object of the invention is to place the retainers within the berth on the entering side so they may be easily accessible from within or without.

A still further object is to so connect the retainers that they may be easily and instantly removed from the berth, which is 55 highly desirable from the fact that the sleep-

ing apartments are usually converted into traveling apartments during the day.

With these and other objects in view, the invention consists in the features of construction, combinations and arrangements of parts hereinafter set forth, illustrated in the accompanying drawings and more particularly pointed out in the claim appended.

In the drawings,

Figure 1 is a view in vertical longitudinal 65 section of a sleeping car apartment to which the improvements are applied, the view being represented in Fig. 2 line *a*—*a* looking in the direction of arrow I.

Fig. 2 is a view in vertical cross section 70 of Fig. 1 on line *b*—*b* looking in the direction of arrows II—II.

Fig. 3 is an enlarged side elevation of the retainer.

Fig. 4 is an end elevation of Fig. 3 on the 75 same scale but with parts removed on lines *c*—*c* and *d*—*d*.

Fig. 5 is the same view as Fig. 4 with certain parts in a different operative position.

Fig. 6 is an enlarged vertical cross section 80 on line *e*—*e* of Fig. 7 looking in the direction of arrows III—III.

Fig. 7 is an elevation of a fragment of Fig. 1, same construction, but with certain parts in different positions.

Fig. 8 is an enlarged view of a modified manner of suspending the retainer.

Fig. 9 is a vertical cross section of Fig. 8 on line *f*—*f* looking in the direction of arrows IIII—IIII.

The apartment is formed as usual with end walls 1 and curtains 2 which are hung from the pole 3 by hooks 4 connecting with the curtain through rings 5 and contains the berths 6 and 7, the lower portion of which 95 terminates in beds 8 and 9 respectively.

The retainer is preferably formed of a single piece of wire forming an eye at 10 to receive the strap 11 and is twisted at 12, 13, 14 and 15 to form a cross with vertical 100 and horizontal arms. The horizontal arms 13 and 15 extending outward in double wire section angling downward to 16 and curved downward at either end forming a hook at 17 to make width for the purpose of fitting the upper part of a coat or other garment and holding it in a similar position as that assumed when worn by a person. The lower arms 21 extend outward and downward from 12, forming an arc from 18 to 19, the 110

outer ends being connected by horizontal portion 20 which is in double wire section. The end portions of the wire follow the arc from 19 to 18 and are adjacent thereto, 5 the ends 18 being coiled around the outward extending portions of the wire at 21.

It is obvious that both arcs 18, 19 and horizontal portion 20 are in double wire section and that the portions 20 may be sprung 10 and separated as in Fig. 5. The object of this is to insert a lady's skirt, a gentleman's trousers or other garments between the portions 20, allowing them to spring together and grip the article, holding it free from 15 becoming wrinkled or mussed.

Collars 22 are provided to pull down in the position shown in Figs. 3 and 4 to increase the grip of portions 20, and are raised as shown in Fig. 5 when it is desired 20 to release the article.

From the foregoing it will be understood that arms 16 and 17 will hold such articles as vests, coats, ladies' waists and the like, while arms 19, 19, 20 will hold gentlemen's 25 trousers, ladies' skirts and the like and the garments will not become crumpled or unpresentable because they will hang in an even and smooth position.

The retainer is secured to strap 11 to 30 which is secured hook 24 which in turn is suspended from the pole 3 as shown in Figs. 1 and 2, or the hook 24 may engage the eye 5 as illustrated in the enlarged views Figs. 6 and 7.

35 It is not desired to restrict the retainer to the construction shown, or the manner of hanging as it is obvious that other forms of retainers and methods of hanging may be employed. It is preferable, however, to 40 hang the retainer on the entering side of the berth for the reasons that it is more easily accessible from both within and without and the strap 11 may extend into the lower berth without interfering with the 45 beds 8 and 9.

Whether the retainer be hung from the pole 3 as in Figs. 1 and 2 or from the eye 5 as in Figs. 6 and 7 it is easily removable when it is desired to convert the sleeping 50 apartment into a day apartment.

The curtains 2 are usually hung from the pole 3 by night and removed during the day.

Copies of this patent may be obtained for five cents each, by addressing the "Commissioner of Patents, Washington, D. C."

It is obvious that if the retainer be hung as in Figs. 6 and 7 it will be removed with the curtain, while if it is hung as in Figs. 1 and 55 2 it can easily be removed by detaching the hook 24 from the pole 3.

In the modified form illustrated in Figs. 8 and 9 the strap 11 is secured direct to the curtain 2, the hook 24 being omitted, and it 60 does not differ from the foregoing description in any other particular. This form is convenient from the fact that hanging the curtains places the retainer in position and removing the curtain removes the retainer. 65

The clothes retainer is of chief importance for railway cars and the like, but may be advantageously employed in state rooms of vessels and the like. It is obvious that numerous changes may be made in the details as set forth without departure from the essential of the invention. 70

Having described my invention, what I claim as new and desire to secure by Letters Patent, is:—

A clothes retainer comprising a single wire, a short straight portion of said wire in the center of the length thereof adapted to have a strap permanently secured thereto, the remaining portions of said wire bent 80 downward, said portions twisted together forming a half twist a short distance from said straight portion and extending approximately in opposite directions to a distance to form a support for a coat thereon, 85 returned and cross the opposite directed portions forming a half twist near said twisted portion and then twisted together forming a half twist below said coat supporting portion, bent in curved opposite 90 directions forming a wide and low arc, then straight toward and paralleling each other to the opposite sides of said arc and paralleling said arc to near the top of said arc and secured thereto by a single twist, and means 95 on said portions forming said arc to tighten said straight paralleling portions.

In testimony whereof I affix my signature in the presence of two witnesses.

NELVIA E. RITCHIE.
